J. Franklin Peigart

UNITED STATES PATENT OFFICE.

STEPHEN L. GEORGE, OF DECATUR, MICHIGAN.

IMPROVEMENT IN CLOTHES-DRIERS.

Specification forming part of Letters Patent No. 56,926, dated August 7, 1866.

To all whom it may concern.

Be it known that I, STEPHEN L. GEORGE, of Decatur, Van Buren county, State of Michigan, have invented an Improved Clothes Drier and Carrier; and I do hereby declare the following to be an exact description thereof, reference being had to the accompanying drawings, and to the letters of reference marked thereon, making a part of this specification.

The nature of my invention is the arrangement, construction, and combination of the crank, pulleys, and posts as a portable clothes drier and carrier, so as not to expose the washer-woman to the weather.

A represents the plank, with an upright post, B, at each end. The tops of the posts are cut out for the pulleys C C to fit and operate in. Near the bottom of the posts are two mortises with two other pulleys, D D. A crank, E, is attached to the first pulley C.

Through the center of the crank-post B there is an adjustable arm, F, with a key, G, to shorten or lengthen the arm by apertures H, in which the key or pin G is inserted. The outer end of the arm is broad and mortised

for the tightening-pulley K to operate in. The posts may be lengthened or extended to any distance apart required. The rope or clothes-line L is drawn around the pulleys from post to post, and tightened by drawing out the arm F. The post B, with the arm F and crank-pulley C, is placed at the back door of a house or under a shed, protected from the sun or weather, and as each piece of cloth is hung on the line the crank E is turned, and the clothes are carried the whole length of the rope; and again, by reversing the crank, the clothes are taken off when dried.

What I claim as my invention, and desire to secure by Letters Patent, is—

The arrangement and combination of the crank-pulley C, tightening-pulley K, grooved pulleys D D, with the posts B B, constructed and operated as herein described, and for the purposes set forth.

STEPHEN L. GEORGE.
